PAPER WEB SUPPORT

John B. Janney, Philadelphia, Pa., assignor, by
mesne assignments, to American Sales Book
Company, Inc., a corporation of Delaware

Application March 6, 1931, Serial No. 520,611

6 Claims. (Cl. 197—133)

This invention relates to paper web supports and particularly to actuating devices therefor.

In the use of fan-fold packs of manifolding sheets with typewriters it has been difficult in the past to prevent "fanning" of the sheets and to preserve prior alignment with the typewriter platen, owing to the inadequacy of supporting devices previously commercially available. Although attempts have been made to provide manifolding web supports supposed to maintain rectilinear alignment of the platen and the web support despite the movements of the platen, yet it has been found that in every case the advantages obtained were overbalanced in importance by the difficulties encountered and the disadvantages made manifest. One major difficulty with prior devices has been that the load of the paper web support has been wholly or in part carried by the typewriter carriage with a consequent substantially inevitable retardation of the free movement of the platen and carriage.

It is among the objects of this invention to obviate the difficulties of prior constructions of web supports; to provide improved means for securing lateral movement of the web support in synchronism with the movement of the typewriter carriage; to provide a driving arm for engagement with a typewriter carriage and a web support which is completely operable regardless of the relative elevations of the web support and typewriter carriage and regardless of the vertical shifting of the carriage; to provide an improved web support; to provide a novel clamp device for positioning a web support at a desired point; to provide a web support arranged for operable association with and disassociation from a typewriter in a small time interval; to provide a web support with a typewriter actuated arm with means for securing lateral adjustment of the typewriter arm to allow for application of the web support to typewriters of various sizes or widths; to provide an efficient simple web support at a minimum of cost; and many other objects and advantages as will become more apparent as the description proceeds.

In the accompanying drawings:

Fig. 1 represents a side elevation partially in section of one embodiment of the invention for web supports.

Fig. 2 represents a top plan thereof illustrating in dotted and full lines, a dividing panel and its frictional engagement.

Fig. 3 represents a side elevation of a modified form of the invention.

Fig. 4 represents a plan of the modified form shown in Fig. 3.

Fig. 5 represents a fragmentary section of that part of the invention which is common to either the preferred or modified form.

Fig. 6 represents a fragmentary transverse section of the device shown in Fig. 5.

Fig. 7 represents a slightly modified fragmentary section, partially in elevation, of the actuating arm disclosed in Fig. 1, and

Fig. 8 represents a fragmentary elevation, partially in section, of a modified form of clamp for the support of a swinging arm.

In the preferred embodiment of the invention a supporting base for the web support is embodied in a semi-permanent or detachable clamping bracket 10 having a desk engaging flange 11 arranged to overlie the edge of a desk or table and underlying flange 12 carrying the threadably adjustable clamping head 13 arranged to engage an under surface of the desk or table by means of the handle 14. The edge of the desk is indicated at 15 and will be understood to be either a portion of the same desk which supports the typewriter 16 or any other independent element. It will be understood that the clamping arm 10 may equally well engage the corner of an article of furniture and that the rigid and immovable arm 17 may extend in any desired direction relative to said corner. As shown in Fig. 8 the arm 17 may, at its inner end, terminate in an enlarged head 1, having a vertical bore 2, arranged to seat upon an upstanding pintle 3, carried by the clamping bracket already described, and to be locked in rigid engagement therewith in any desired manner, as by fluting or keys (not shown) or by a locking device such as the wing bolt 4, threaded into pintle 3. The end of the arm 17 in either form of the bracket has an enlarged hub 18 having a vertical axial opening or socket to receive the downwardly extending pintle 20 of a swinging arm 21. It will be understood that the pintle 20 is received in the socket of the hub 18 with an anti-friction relation so that arm 21 swings freely relative to arm 17. The free end of arm 21 is also provided with an enlargement 22 having a vertical axial socket such as to receive the pintle 23 of the bearing to be described.

The web support may comprise simply the flat bed 25 forming a bottom of the box 24. The box 24 or bed 25 is arranged to receive and support a manifolding fan-fold pack in operative relation to the platen of the typewriter to be described. The box 24 or bed 25 thereof is mount-

ed symmetrically upon a flange 26 terminating in the coaxial pintle 23, previously mentioned, but having the integral radial projection 27 as a substantial prolongation of the flange 26 and with its upper surface lying in the plane of the upper portion of the flange. The projection 27 may be of any desired size or contour in cross section, but is preferably formed as a channel having depending substantially radial ribs 28 which terminate beyond the edge of the box 24 or bed 25 in a clamp 30 either cast or formed rigidly with the ribs 28 or attached thereto in any desired manner. The clamp 30, which may be of any desired sort, preferably has a central bore 31 of variable size according to the pressure exerted on the upstanding ears 32 of the clamp by the threaded bar 33 as shown in Fig. 6. An arm 34 is slidably mounted in the bore 31 and extends between the ribs 28 of the projection 27 toward the axis of the flange 26. Owing to the arrangement of the clamp it will be observed that the arm 34 may have very fine adjustments in telescoping relation to the projection 27 so that the outer end 35 of the arm, of reduced diameter, may be located at any desired point relative to the axis of the web supports concentric with the pintle 23.

It will be understood that the function of the web support is to support a fan-fold pack or web in operative rectilinearly aligned association with the platen or carriage of the typewriter 16. To this end it is desirable that a permanent attachment be made to the typewriter suitable for guiding directing actuation of the web support during their operative association but so arranged as to permit quick disassociation of the web support and thereafter the continued operation of the typewriter without reduced efficiency despite the presence of the permanent attachment. Although such attachment may take various forms according to the structural limitations of the typewriters with which it may be associated, such device is disclosed in Figs. 1, 2, 3, and 4, as comprising a bar 36 permanently mounted upon the marginal bar 37 or other movable part of the typewriter carriage, and terminating in a cylindrical portion 38, either in alignment with the bar 36, or in spaced parallel relation thereto by means of an upstanding portion 40. In any case it is preferred that the cylindrical end 38 be in parallelism with the marginal bar 37 and perpendicular to the longitudinal axis of the typewriter. (For the purpose of this specification it will be understood that the longitudinal axis of the typewriter is that extending from the front or key board backwardly toward the rear of the machine.) It will be understood that the cylindrical portion 38 permanently attached to the typewriter carriage in any desired manner, and the reduced end 35 of the bar 34, adjustably but permanently connected with the web support, are each provided with quick detachable spring clips 41 to permit instant attachment and detachment of either form of guiding arm disclosed. The clips engage in peripheral grooves, as 29, in the respective portions.

In the preferred form of the invention a telescoping arm is provided comprising a hollow tubular telescope element 42 pivotally connected by the bearing portion 43 to the cylindrical end 38 of the typewriter attachment. The complementary portion of the telescoping arm comprises a rod, bar or tube 44, pivotally mounted by means of the bearing 45 to the reduced end 35

of the adjustable arm 34 and having telescoping sliding engagement within tube 42. It is preferred that there be appreciable overlapping of the tube 42 upon the rod or tube 44 so as to afford adequate guiding engagement. As shown in Fig. 7 the rod 44 may have sliding engagement through a nipple or collar 19, made of such material for instance, as fiber, if sound insulation is required, or which may be made of metal, and which takes half of the lateral stresses incident to movement of the typewriter carriage. The other half of the stress may be carried by a plug 9, of similar material, mounted on the end of rod 44. This modified arrangement may be substituted for the elongated bushing 8, shown in Fig. 1. The important feature being that there be clearance in either telescoping form to permit free axial movement.

In the other form of guiding arm the bearing 46 rotatably mounted on the typewriter attachment preferably by means of a "self-aligning" bearing, supports a rigid rod 47 pivoted with a knee joint 48 to a cooperating or complementary rod 50, which in turn is pivoted by means of a bearing 51 (which has no lateral play) to the reduced end 35 of the adjustable arm 34. In this form of the invention the knee joint 48 can be so arranged as to give any desired degree of hinging action but may be provided with suitable steps to prevent the knee joint from straightening out toward or past dead center.

It will be understood that some types of typewriters change the case by vertically shifting the platen. With either of the forms of arm disclosed herein such vertical shifting will be almost completely absorbed in the bearings of the ends of the arms. This is because the bearings must have sufficient clearance to move freely when desired, and this clearance may easily be such as to compensate for the very slight movement longitudinally occasioned by such case shifting. If this vertical movement is exaggerated in some particular typewriter then the telescoping or bending arms will absorb the longitudinal movement of the vertical shift. Similarly any deviation in levels of the typewriter carriage and the web support such as may occur due to different types of desks with which the two are associated is immediately compensated for by the pivotal connection of either arm at each end thereof in connection with its elongation factor incident to telescoping or folding. Then again, with the mounting for the web support disclosed herein oscillating on a swinging arm, there is longitudinal relative movement of the carriage and the web support, due to the arcuate path of the web support. This is compensated for by the telescoping or bending of either arm which may be used. Thus although the synchronized movement of the typewriter carriage and web support is in a horizontal plane, it will be observed that relative movement of the carriage and web support may take place in three perpendicular planes, of which one possible relative movement (in the horizontal plane) is precluded by the driving engagement of the arms, but that the other two may take place simultaneously without adverse effect on the rectilinear alignment of the web support and platen or carriage.

The alignment of the web support 24 with the typewriter platen is a simple and easy accomplishment.

It is a feature of the invention that the box 24 has a movable dividing panel capable of instant adjustment to form a lateral guide for one side

of a fan-fold pack with the side of the box forming the complementary parallel guide. To this end the panel 52, of smaller length than the side of the box, is provided with friction spring plates 53, which as shown in Fig. 2 in full lines, engage the ends of the box 24 when it is to be adjusted so that the panel 52 is not parallel with the sides of the box. Swinging movement to parallelism, causes the plates to be flexed and frictionally retain the given guiding position.

It may be noted that variations in size of typewriter carriage may be compensated for by movement of the arm 34 relative to the axis of the support or of the points to be aligned. The assembly provides a certain, positive, quiet actuator to cause the web support to swing about the pivot formed by pivot 28, to maintain the bodily alignment of the typewriter carriage and web support and simultaneously to cause the web support and swinging arm 21 to have relative movement such as to contribute toward the rectilinear alignment of the support and the typewriter carriage.

Clearly the driving arm disclosed may be associated with other forms of web supports, such as those traveling on a track, although the track has many disadvantages not attaching to the invention disclosed herein.

I claim:

1. In a web controlling apparatus for writing machines, in combination, a movably mounted web controlling attachment, and an operating arm for said attachment having telescopically engaging parts pivoted respectively to the writing machine and to said controlling attachment, one of said pivotal connections being laterally extensible and retractable.

2. In a web controlling apparatus for writing machines, in combination, a web supporting bed, a pintle symmetrically associated with said bed, a telescoping operating arm pivoted to the bed through said pintle, and telescoping for radial adjustment between the pintle and machine, and a pivotal connection with the opposite end of the telescoping arm for laterally actuating the bed by operation of the writing machine, said pintle being adjustable longitudinally of its axis on said supporting bed, and a swinging supporting arm on which said bed is pivotally supported.

3. In a web controlling apparatus for writing machines, in combination, a laterally movable carriage for the machine, a web support mounted for lateral swinging movement in a plane substantially parallel to that in which said carriage moves, an extensible and contractible driving connection between said carriage and said support, and connecting pins on said carriage and web support having their axes substantially parallel to the path of carriage feed to which the driving connection is respectively attached to provide pivotal connections, said driving con-

nnection including an arm extending between the carriage and web support and pivotally connected through said connecting pins, and said arm having sections with adjacent end portions intermediate the arm ends and intermediate said pivotal connections overlapping telescopically with each other to an appreciable extent in all operative positions so as to transmit driving effort without undue lateral flexure.

4. In a web controlling apparatus for writing machines, in combination, a web support, means for supporting said web support for horizontal movement, a driving connection between said web support and the carriage of the writing machine, including a connecting pin, having a telescopic longitudinal adjusting connection with said supporting means, and a clamp on said supporting means for anchoring the connecting pin in adjusted position.

5. In a web controlling apparatus for writing machines, in combination, a web support mounted for lateral movement, a driving link including sections having sliding contacting connection with each other at points thereof intermediate its ends and longitudinally spaced a material distance to provide for transmission of lateral thrusts, said driving link having one of its ends pivotally connected to said web support and having another end pivoted to a movable part of the writing machine, and the axes of said pivotal connections being substantially parallel to the movement of said movable part of the writing machine.

6. In a web controlling apparatus for writing machines, in combination, a writing machine having a laterally movable carriage mounted for vertical movement and for case-shifting, a web support, a horizontally swingable supporting arm on the swinging end of which said web support is mounted, means connecting the carriage and the web support for synchronized lateral movements, said connecting means including link sections connected together for extension and retraction so that the arcuate movements of the web support and the vertical shifting of the carriage do not disturb the synchronized lateral movements of both carriage and web support, the connection between said link sections being sufficiently rigid in the direction of carriage letter-spacing movement to transmit operating effort therethrough to said web support but being flexible at right angles to said letter-spacing movements to permit free movements of said web support in a horizontal arc, the sections of said connecting means being pivoted respectively to said carriage and to said web support, and the pivotal connection with the web support including a pintle symmetrically associated with said web support and mounted for longitudinal adjustment thereon.

JOHN B. JANNEY. 60
